(57) **CLAIM**

The ornamental design for a display screen or portion thereof with graphical user interface, as shown and described.

DESCRIPTION

FIG. 1 is a front view of a display screen or portion thereof with graphical user interface in accordance with a preferred embodiment of my new design, wherein the display is in an unelectrified state; and,

FIG. 2 is a front view thereof, wherein the display is in an electrified state.

The broken lines shown in the drawings illustrating the display screen form no part of the claimed design.

1 Claim, 2 Drawing Sheets Fig. 1
